NEWS AND ADVERTISEMENT EXHIBITING

Arthur A. Johnson, Bridgeport, Conn.

Application July 27, 1935, Serial No. 33,449

23 Claims. (Cl. 40—52)

This invention relates to the art of presenting at intervals a series of prearranged advertisements or other displays for exhibition and alternately therewith news items or other matter written at the time or just previous to its exhibition. The writing of the news items may be controlled and performed by a person at the place of exhibition, but usually the writing is done on an electrically operated typewriter telegraphically controlled, and hence operable from a remote point. In fact, many such typewriters at widely separated places may be simultaneously operated from a single point.

In such exhibiting machines as heretofore provided, the news items were typewritten on a continuous web or strip of paper having alternate advertising and writing zones thereon, the advertising being previously printed on the strips and the writing zone being usually left entirely blank. The strip is fed through the telegraphic typewriter and advanced line-by-line as the news items are written on it. A reflectoscope is placed in front of the typewriter to pick up and show on a suitably placed screen the matter typewritten on the strip. After the audience has had time to read the news items, the strip is advanced to bring the advertisement printed thereon into range of the reflectoscope and allowed to remain there as long as desired, usually for a predetermined time.

With this arrangement, the number of different advertisements which may be exhibited is extremely limited, for, with the printing equipment available at present which is capable of printing continuous strips, it is not possible to repeatedly print on the strip more than two or three advertisements of desired size alternated with writing spaces or zones of suitable size because of the limited feeding throw and limited printing area of the cylinders or platens.

If the advertisements were to be printed in one color, by increasing the feeding throw of the press and using multiple cylinders or bed, the number of different advertisements printed could be increased somewhat. However, in order that the advertisement may be effective, it is desired that it be printed in colors and in the characteristic colors usually used by the advertisers.

It is desired to avoid the limitation of the use of such exhibiting machines above referred to and to permit any desired number of different advertisements to be used in a series and to permit these to be economically and conveniently printed by existing machinery in any desired colors and any desired number of different colors.

This is accomplished in the application of Carl W. Brenn, filed January 31, 1935, Serial No. 4,224, by providing the advertisement on a web or strip separate and independent of the writing strip, causing the latter to be superimposed on the former on the platen of the typewriter and arranging the strip so that the portions of the under strips which are to be viewed will be visible through the upper strip. The advertising strip has its ends united to form an endless band so as to repeatedly present successive portions thereof to view.

An object of this invention is to provide means whereby the display band and the writing strip may advance together during the writing of the news item and the display band alone advanced to bring a new advertisement into position to be shown independently of the writing strip and between the operations of typing successive news items.

A further object of this invention is to prevent operation of the type mechanism while an advertisement area on the display band is in the line of writing of the typewriter platen, thereby avoiding even partial obliteration of the display by typewriting thereon.

Another object of this invention is to provide means whereby the display band may be allowed to remain in a stationary position during the typewriting of a news item so that after the completion of the typewriting the display band may be advanced to bring a new advertisement into view without advancing the writing strip.

In either arrangement above referred to, the feeding of the writing strip and master band may be controlled entirely from a remote point so that the band and strip may be fed together or separately as desired. However, means are provided by the present invention whereby the feeding of either the band or strip or the band and strip may be automatically controlled by the typewriting machine so that when the writing strip and display band have been advanced a predetermined amount (the length of the maximum news item) the feed mechanism for the writing strip is rendered inoperative while the feed mechanism for the display band continues to operate.

In the first form of the invention above referred to, the means may be so arranged that when the writing strip has advanced independently of the display band one form length, i. e. the length of the maximum news item, the feeding of the writing strip ceases and the feeding of the display band begins and continues until the next display is moved into position to be shown.

According to the broader aspects of this invention, any suitable means may be used for rendering the typing mechanism inoperative while the advertisement or other display is in such position that it would be printed upon by the types.

In one form of this invention, this is accomplished by providing means mechanically synchronized with the platen and feed mechanisms of the machine for rendering the typewriting mechanism inoperative.

Other features and advantages will hereinafter appear.

In the accompanying drawings:—

Figure 1 is a perspective view showing the continuous display band of the present invention with the writing strip located between the band and the platen.

Fig. 2 is a schematic view showing the mechanism for advancing the display band and the writing strip and controlling the intermittent feed of these selectively.

Fig. 3 is a side view of the arrangement shown in Fig. 1.

Fig. 4 is a schematic view of a modified form of feed device wherein the writing strip and display band are for the most part fed alternately, the one strip beginning to feed at a predetermined time when the other strip stops feeding.

Fig. 5 shows diagrammatically an arrangement for synchronizing all of the receiving machines.

In the embodiment of this invention illustrated in Figs. 1, 2 and 3, the writing strip 10 is led from a supply pack 11 over a guiding and tensioning drum 12 and thence over a turning bar 13 so as to extend forwardly and around a platen 14 mounted on a shaft 15. The writing strip extends upwardly over a display table 16 and over a guide drum 17 where it extends rearwardly, then over a turning bar 18 from which it extends laterally to a feed drum 19 mounted on a shaft 20.

Superimposed over the writing strip 10 while the latter is on the platen and on the display table there is a display band 21. This band has its ends joined so as to be continuous and passes around the platen 14 upwardly over the display table, then rearwardly over a guide roller 22, then downwardly over a guide roller 23, and then forwardly over a guide roller 24 from which it is led to the platen.

In order to maintain the writing strip 10 and the display band 21 in coordination with the platen and feeding mechanism, the writing strip is provided with marginal feed holes 25 and the display band is provided with marginal feed holes 26, and the feeding drum 19 is provided with feed pins 27 for engaging and feeding the writing strip while the platen 14 is provided with feeding pins 28 for feeding the display band 21. The writing strip 10 is made sufficiently narrower than the display band 21 so that its lateral edges will pass inside of the rows of pins 28 on the platen. Hence, the writing strip will not be fed by the platen but only by the feeding drum 19.

To tension the writing strip when it is supplied from a zigzag folded pack as shown, the roller 12 is provided with pins 29, and the roller is provided with a brake drum 30 engaged by a spring 31, to yieldingly retard rotation of the drum and hence provide a drag on the writing strip.

To advance the display band, the platen is provided with a ratchet wheel 32 secured to the shaft 15, and, in the form of the invention herein shown as exemplary thereof, is operated by a pawl 33 on an arm 34 connected by a link 35 to

an armature 36 of a solenoid 37. The rocking movement of the arm 34 is limited by a stop screw 38 engaging an extension 39 on the arm 34 so that at each operation of the solenoid 37 the platen is rotated a predetermined amount. By adjusting the stop screw 38, the amount of movement of the platen may be limited to one line space, or it may be varied to advance the platen two or more line spaces if desired, and this is desirable where, as above stated, the display band is advanced independently of the writing strip.

The writing strip is likewise fed by a pawl and ratchet mechanism, the shaft 20 for the feeding drum being provided with a ratchet wheel 40 which, in the embodiment of the invention illustrated herein as exemplary thereof, is operated by a pawl 41 on an arm 42 connected by a link 43 to an armature 44 of a solenoid 45. The extent of movement of the arm 41 is controlled by a stop screw 46 engaging an extension 47 on the arm 42.

It should be understood, of course, that other means for mechanically advancing the writing strip and display band may be employed if desired.

As diagrammatically illustrated, the display band 21 is provided with a succession of advertisements 48, and, in order that the news items may be typewritten upon the writing strip 10 as by types 49 in spite of the overlying display band 21, the latter is provided with cut-outs or windows 50 alternating with the advertisements 48.

As the display band is fed, the windows 50 are brought successively to the position shown in Fig. 1 in which it exposes the writing strip so that the latter may be typewritten upon. If, as may be desired, the writing strip 10 and display band 21 are advanced in unison, the typewriting of a news item, for instance, may be continued on the writing strip until the bottom edge of the window 50 reaches the writing line, during which time the advertisement 48 is located on the display table to be shown. At this position, the strips may continue to be advanced in unison until the next advertisement is brought into position to be shown and its next adjacent window is located over the writing line of the platen. However, this would necessitate the wasting of portions of the writing strip equivalent to the area covered by the advertisements 48, and to avoid this the present invention provides for advancing the display band independently of the writing strip.

In the form of the invention shown in Figs. 1 to 3, the writing strip and display band are advanced together during the writing of a news item on the writing strip, and this may be accomplished by connecting the solenoids 37 and 45 to supply wires 51 and 51a and connecting them in series by a wire 52 so that each time the solenoid 37 operates, the solenoid 45 operates when typewriting. When the bottom edge of the window 50 approaches the writing line, however, in this form of the invention the feeding of the writing strip is interrupted and impulses transmitted over the wires 51 and 51a advance only the display band.

This is shown in the form of the invention illustrated in Figs. 1 to 3 by shunting out the solenoid 45 and it is accomplished automatically and without attention on the part of the operator by a controller 53, see Fig. 2, connected to the platen shaft 15 by gears 54 and 55. The ratio of these gears is such that the controller makes one

complete revolution during the feeding of one advertisement 48 plus one window 50. One-half of the face of the controller has insulation 56 while the other half has a metal segment 57, and 5 resting against the face of the controller are three brushes 58, 59 and 60, the brush 58 being connected to the point where the wires 51 connect with the solenoid 45 and the brush 59 being connected to the wire 52 which connects 10 the solenoids 37 and 45 together in series. Thus, when the brushes 59 and 60 both engage the metal portion 57 of the controller, current passing from the line 51 is shunted around the solenoid 45 and passes directly through the controller to the solenoid 37, thereby rendering the 15 solenoid 45 and the feed mechanism for the writing strip inoperative. The parts are shown in Fig. 2 in the positions which they occupy just at the time that the lower edge of the window 50 approaches the writing line. At this time, in the 20 form of the invention now being described, the writing strip remains stationary and the display band advances alone.

Thus shunting out of the writing paper feed 25 solenoid 45 continues until the upper edge of the next window 50 has passed beyond the writing line of the platen.

At the same time, through the brush 59, metal segment 57 and brush 60, current passes to a relay 30 which locks out or renders inoperative the printing mechanism of the machine so that typewriting cannot be performed during the time that the display or advertisement portion of the band 21 is located in writing position on the platen, it 35 is being understood, of course, that the line 51 is permanently connected to one side of the source of current while the relay or other means which locks out the printing mechanism is connected to the other side of the source of current.

40 The predetermined extent of feed of the writing strip may be anything desired, but in the form shown, the extent of feed of the display band should be equal to one display zone plus one window.

45 This is accomplished as shown in Fig. 4 by providing separate controllers 65 and 66 for the display band 21 and writing strips 10 respectively. The controller 65 for the display band comprises a contact disk 67 and is geared to the platen 14 in such a way that the disk makes one revolution 50 when the platen has rotated sufficiently to advance the display band one form-length, that is, the length of one display area and one window, while the controller 66 is geared to the feed drum 19 for the writing strip so that it will make one 55 revolution when the writing strip has advanced the extent equal to the length of the maximum area occupied by the longest news item. This may be as long as the window or shorter or longer 60 if desired, since the display band is stationary while the news item is being printed.

The display band controller 65 has a metal face 67a interrupted at one point by an insulating portion 68, and riding on the face 67a there 65 is a contact 69 connected by a wire 70 to the solenoid 37 which advances the display band. Another brush rides on the shaft 71 of the controller and this is connected to a wire 72 leading from the contactor which is operated when it is desired 70 to advance either the band or the strip. The other wire 73 from the contactor is connected to the solenoid 45, and hence when current passes through the wires 72 and 73, and the contact 69 is on the face 67a of the controller 65, the solenoid 75 37 is operated and the display band is advanced.

When the display band has been advanced to a predetermined point, the insulator 68 engages the contact 69 and opens the circuit and renders the advancing means for the display band inoperative.

5

The controller 66 for the writing strip also has a metal face 75, an insulation portion 76, brush 77 on the face 75, and a shaft-brush on the controller shaft, which is connected to the wire 72 to which the shaft-brush of the display band controller is connected. The brush 77, however, is connected by a wire 78 to the solenoid 45 which operates the feed drum for the writing strip, the solenoid 45 being connected to the wire 73 leading from the line spacing contactor (not shown). Hence, the feeding of the writing strip ceases when the brush 77 rides on the insulation 76.

10

To cause the feeding of the display band to be resumed upon cessation of feed of the writing strip, the controller for the latter is provided with a contact 79 in position to engage a brush 80 at the last line of writing of the news item. This brush 80 is connected to the wire 79 leading to the solenoid 37 of the feeding mechanism for the display band, so that the next time current flows through the wires 72 and 73 both the display band and the writing strip will be advanced one line space and their controllers will be moved one step, bringing the insulation 76 on the writing strip controller under the brush 77 and moving the insulation 68 on the display band from under the brush 69, shifting the connections of the wires 72 from the solenoid 45 for the writing strip to the solenoid 37 for the display band.

20

Likewise, the display band controller has a contact 81 and a brush 82 connected to the wire 78 of the writing strip solenoid 45 so that it will cause the feed of the writing strip to be initiated just before cessation of feed of the display band.

25

When, as is usual, a number of machines are controlled from a single sending machine located at a remote point, there is a possibility that the various machines may be out of synchronism. This could be caused by the supply current being cut off at the receiving machine at some time during its operation and might cause the display band being left with a display at 45 the line of writing at one receiving machine while at the others and at the sending machine, the display may be out of the line of writing and in position to permit typewriting on the writing strip. The result would be that the type mechanism would print on the display area and obliterate or spoil the appearance of the display.

30

This is avoided in the form of the invention shown in Figs. 1 to 3 by preventing printing at 60 such times.

35

However, the present invention provides means whereby the sending machine operator may bring the display bands of all the receiving machines to one predetermined and known 65 starting position, and this may be done at the start of the day or periodically or at any time desired.

40

To accomplish this, the contactors of the sending and receiving machines are so arranged 70 that by operating a special key a synchronizing circuit comprising wires 83 and 84 (Fig. 5) is energized. The wire 84 is connected to the solenoid 37, for the display band feeding machine, while the other wire 83 is connected by a wire 75

85 to a contact finger 86 over a contact bar 87 which is connected by a wire 88 through the wire 52 and solenoid 37 to the opposite side of the synchronizing circuit.

5 The contact bar 87 and the contact finger 86 are normally connected by the display band which, in this case, is made of metal, and hence when the impulses are sent over the wires 83 and 84 the electromagnet 37 will be energized 10 to advance the writing strip and display band step-by-step without regard to the position of the contact 59 with relation to the controller contact 57 or the insulation 56, the latter being arranged substantially as shown in Fig. 2 except that the contact 60, which in Fig. 2 is employed to lock the printing mechanism at certain times, is not required in the form of the invention now being described.

This advancement of the writing strip and 20 display band will continue in all the machines connected to the sending machine until the display bands on the respective machines reach a predetermined starting position. This is controlled by a piece of insulation 89 on the metal 25 display band located between the contact finger 86 and the contact bar 87. When the display band of one of the machines reaches the position where the insulation 89 is interposed between the contact finger 86 and the contact bar 30 87, the synchronizing circuit to that machine is opened, and further impulses will have no effect on advancing that display band.

Thus it will be seen that if impulses are sent 35 over the synchronizing circuit sufficient to advance the display band and writing strip through one form length, i. e. a length including the display area and the writing area in each machine, the display band and the writing strip will advance until they come to a predetermined 40 definite position.

Variations and modifications may be made within the scope of this invention and portions of the improvements may be used without others.

45 Having thus described the invention, what is claimed as new and for which it is desired to obtain Letters Patent, is:—

1. In a machine of the character described, the combination of an endless display band for holding 50 for exhibition, one at a time, a plurality of advertisements; a writing strip; type mechanism; a platen over which said writing strip is advanced to receive impressions from said type mechanism to be exhibited, said display band being led 55 around the platen and being superimposed on said writing strip at the platen and having windows through which the type mechanism may reach and strike the writing strip carried by the platen to print news items thereon.

60 2. The invention as defined in claim 1 in which the windows are of substantial size so that a news item of several lines may be displayed through each window.

3. The invention as defined in claim 1 in which 65 the display band and writing strip each has a separate feed mechanism so that the one may be advanced without the other.

4. The invention as defined in claim 1 in which 70 a feed mechanism is provided to advance the display band independently of the writing strip.

5. The invention as defined in claim 1 in which a feed mechanism is provided to advance the writing strip independently of the display band.

6. The invention as defined in claim 1 in which 75 there are provided separate feed mechanisms for

advancing the display band and writing strip and means for causing both said feed mechanisms to operate together.

7. The invention as defined in claim 1 in which there are provided separate feed mechanisms for advancing the display band and writing strip and means for causing both said feed mechanisms to operate together when the news item is being written and only the feed mechanism for the display band when the display area on the display band is being advanced past the line of writing of the platen.

8. The invention as defined in claim 1 in which there are provided separate feed mechanisms for advancing the display band and writing strip and means for causing both said feed mechanisms to operate together when the news item is being written and only the feed mechanism for the display band when the display area on the display band is being advanced past the line of writing of the platen, said means being controlled by the platen.

9. The invention as defined in claim 1 in which there are provided separate feed mechanisms for advancing the display band and writing strip and means for causing both said feed mechanisms to operate together when the news item is being written and only the feed mechanism for the display band when the display area on the display band is being advanced past the line of writing of the platen, said means being controlled with movement of the display band.

10. The invention as defined in claim 1 in which there is provided means for rendering the type mechanism inoperative when a display area on the display band is being advanced past the line of writing of the platen.

11. The invention as defined in claim 1 in which there is provided means for rendering the type mechanism inoperative when a display area on the display band is being advanced past the line of writing of the platen, said means being controlled by the typewriter platen.

12. The invention as defined in claim 1 in which there is provided means for rendering the type mechanism inoperative when a display area on the display band is being advanced past the line of writing of the platen, said means being controlled by movement of the display band.

13. The invention according to claim 1, in which there is feed mechanism for advancing the display band independently of the writing strip, and means responsive to alterations of the display band for automatically rendering the said advancing means inoperative when the display band has been brought to predetermined position relative to the platen.

14. The invention according to claim 1, in which there is feed mechanism for advancing the display band independently of the writing strip, and means responsive to alterations of the display band for automatically rendering the said advancing means inoperative when the display band has been brought to a position in which a portion of a window in the display band is located in the line of writing of the platen.

15. The invention according to claim 1, having feed mechanism for advancing the writing strips and display band, and means responsive to alterations of the display band for rendering said feeding means inoperative to advance the display band when the latter has been brought to a predetermined position relative to the platen.

16. The invention according to claim 1, having feed mechanism for advancing the writing strips

and display band, and means responsive to alterations of the display band for rendering said feeding means inoperative to advance the display band when the latter has been brought to a predetermined position relative to the platen feed mechanism for advancing the writing strip and display band, and means responsive to alterations of the display band for rendering said feeding means inoperative to advance the display band 10 when the latter has been brought to predetermined position relative to the platen.

17. The invention according to claim 1, having independent feed mechanism for advancing the writing strip and display band respectively, common means for initiating the operations of said feeding mechanism, and means for automatically controlling the operation of said feed mechanisms to cause feed mechanism to operate alternately so that when the writing strip is fed a predetermined extent, its advancement will cease and the display band has been advanced a predetermined extent its advancement will cease and the writing strip will begin to advance.

18. The invention according to claim 1, having independent feed mechanism for advancing the writing strip and display band respectively, common means for initiating the operations of said feeding mechanism, and means for automatically controlling the operation of said feed mechanisms to cause feed mechanism to operate alternately so that when the writing strip is fed a predetermined extent, its advancement will cease and the display band has been advanced a predetermined extent its advancement will cease and the writing strip will begin to advance and also separate means for initiating the operation of the feeding mechanism for the display band and means responsive to alterations of the display band for rendering said separate initiating means 40 inoperative to cause the advancement of the display band when the latter has been brought to a predetermined position relative to the platen.

19. The invention according to claim 1, having independent feed mechanism for advancing the writing strip and display band respectively, common means for initiating the operations of said feeding mechanism, and means for automatically controlling the operation of said feed mechanisms to cause feed mechanism to operate alternately 50 so that when the writing strip is fed a prede-

termined extent, its advancement will cease and the display band has been advanced a predetermined extent its advancement will cease and the writing strip will begin to advance, said automatic control means including two controllers, one associated with each feeding mechanism and each controller rendering its own feeding mechanism inoperative at predetermined points in the cycle of operation.

20. The invention according to claim 1, having independent feed mechanism for advancing the writing strip and display band respectively, common means for initiating the operations of said feeding mechanism, and means for automatically controlling the operation of said feed mechanisms to cause feed mechanism to operate alternately, so that when the writing strip is fed a predetermined extent, its advancement will cease and the display band has been advanced a predetermined extent its advancement will cease and the writing strip will begin to advance, said automatic control means including two controllers, one associated with each feeding mechanism and each controller rendering its own feeding mechanism inoperative at predetermined points in the cycle of operation, and means controlled by the position of one controller for causing the other feeding mechanism to resume operation.

21. The invention as defined in claim 1, in which there is means responsive to electrical impulses for advancing the writing strip and the display band.

22. The invention as defined in claim 1, in which there are provided separate and independently operative mechanisms responsive to electrical impulses for advancing the display band and writing strip, and a switch periodically actuated by advance of the display band for rendering inoperative the mechanism for advancing the writing strip during advance of the display band.

23. The invention as defined in claim 1, in which there are provided independently operative mechanisms responsive to electrical impulses for advancing the display band and writing strip, and means responsive to predetermined groups of impulses for periodically rendering inoperative the mechanism for advancing the writing strip.

ARTHUR A. JOHNSON. 50
